UNITED STATES PATENT OFFICE

124,258

DESIGN FOR A MOTION PICTURE PROJECTOR

William E. Merriman and Howard C. Wellman,
Rochester, N. Y., assignors to Eastman Kodak
Company, Rochester, N. Y., a corporation of
New Jersey

Application October 30, 1940, Serial No. 96,180

Term of patent 7 years

To all whom it may concern:

Be it known that we, William E. Merriman and Howard C. Wellman, citizens of the United States of America, residing at Rochester, county of Monroe and State of New York, have invented a new, original, and ornamental Design for Motion Picture Projectors, of which the following is a specification, reference being had to the accompanying drawings, forming a part thereof, in which:

Fig. 1 is a perspective view of the motion picture projector showing our new design. The

perspective view is taken from the front and to one side of the projector.

Fig. 2 is a perspective view of the projector shown in Fig. 1, but is taken from the opposite side thereof, showing the back and a portion of the side and top of the projector.

We claim:

The ornamental design for a motion picture projector, substantially as shown.

HOWARD C. WELLMAN.
WILLIAM E. MERRIMAN.
